AUTOMATIC MILLING MACHINE

Frederick Koch, Sparta, N. J., assignor to Associated Patentees, Inc., Ampere, N. J., a corporation of New Jersey

Application December 21, 1939, Serial No. 310,321

19 Claims. (Cl. 90—13)

The invention here disclosed relates to milling machines and is a continuation in part of Patent 2,202,210 of May 28, 1940.

Special objects of the present invention are to provide an automatic miller of the type of said patent which may be readily set and adjusted for different more or less complicated machining operations; which may be employed for many difficult unusual and complicated operations; which while normally fully automatic may be arbitrarily controlled, as for stopping and starting purposes at any time and which in general will be thoroughly practical and efficient.

The foregoing and other desirable objects are attained by novel features of construction, combinations and relations of parts as hereinafter specified, illustrated in the accompanying drawings and broadly covered in the claims.

The drawings illustrate one of the commercial machines embodying the invention, but it will be appreciated from the scope of the claims that structure may be modified and changed in various ways all within the true intent of the invention.

Fig. 1 is a broken part sectional front view of the upper portion of the machine.

Fig. 2 is a similar view of lower parts of the machine.

Fig. 3 is a broken sectional detail showing particularly the double cam mechanism for operating the worktable.

Fig. 4 is a broken plan view of the table movement controlling cam mechanism.

Fig. 5 is a broken plan and part sectional view of portions of the drive mechanism, as on substantially the plane of line 5—5 of Fig. 1.

Fig. 6 is an enlarged broken sectional detail of the special gearing for enabling arbitrary setting of the table operating cam as viewed from the right of the main shaft 52 in Fig. 5.

Fig. 7 is a broken vertical sectional view of the cam means for imparting vertical movements to the spindle head, this view being taken on substantially the plane of line 7—7 of Fig. 1.

Fig. 8 is a broken detail view of the throw-out clutch and latch mechanism.

The machine illustrated embodies many of the features of the patent referred to, including a hollow cabinet type of base 10, providing a housing for the motors and drive mechanism, a reciprocating worktable 11, operated or controlled by cams specially designed to accomplish the exact table movements requisite for different operations and a cutter spindle 12, journaled in a head 13, vertically shiftable on a column 14.

Also, as in the patent identified, movement of the table in one direction is effected by means of a weight 15, and flexible connection 16, running over guide rolls 17, 18, to a point of connection with the table at 19. In the present disclosure however, an extra or follow-up cam is provided to assure the full and complete table movement.

The table operating and controlling cams are shown at 20, 21, Figs. 3 and 4, pinned at 22, in fixed relation on the upper end of shaft 23, in position to respectively engage the rolls 24, 25, on the divergent arms 26, 27, of the cam lever 28, pivoted on vertical axis 29, and carrying gear segment 30, in mesh with the rack 31, on the underside of the worktable or carriage.

The provision of separate edge cams is particularly desirable, since each can be designed to perform its particular function to best advantage and the combination of these with the gravity effected movement of the worktable is especially advantageous for climb milling and operations of that sort.

In Figs. 1 and 2, a flat piece of work 32, is held for a climb milling cut in the work holder 33. It will be noted that the cutter 12, turns downward, instead of upward over the advancing work, tending to draw the work toward it and to assist in holding it in the clamp, instead of tending to pull it out of the clamp. Also that in this work feeding movement, the table is advanced by the weight, with such advancing movement limited and controlled by the cam 20, which is cut to permit the exact movement desired at any or all points in this cutting control of the table. The cam 21, which cooperates with the follower 25, acts in the same direction, that is of the table movement, as the weight 15, but may be so designed as to come into action only at or toward the end of the feed movement, thus to make sure that the table fully completes such feed movement even though permitted to advance to the cutter under gravity feed for the major portion of such movement.

Vertical movement of the cutter head is effected in the present machine by similar double cam mechanism. No weight however is required, such as used with the horizontal table feed, since the weight of the vertically moving cutter head is sufficient to maintain a desired relation between the cam and follower in the lowering movement of the head.

Referring to Figs. 1 and 4, the cutter head 13, guided in ways 34, is shown as having a rack 35, engaged by the gear segment 36, of cam lever

37, pivoted at 38, and having one arm 39, carrying one roll 40, tracking on edge cam 41, controlling downward movement of the cutter head and a second arm 42, carrying a roll 43, at the opposite, upper side of the pivot center engaged by the other, separate lifting cam 44.

These cutter head cams, designed to cooperatively accomplish the desired cutter head movements, are removably secured in fixed relation on the shaft 45, journalled horizontally in a partition wall 46, in the hollow column 14. This shaft, at the back of the partition carries the worm gear 47, in mesh with a worm 48, on the angularly related horizontal shaft 49, and the latter is driven through bevel gears 50, from a vertical shaft 51, at the back of the machine extending from the cabinet portion of the base up into the hollow column, back of the partition.

Both sets of cams, those for horizontal reciprocation of the table and those for vertical movement of the cutter head are maintained in properly timed relation by being driven from the same power source, in this instance, the so-called main shaft 52, Fig. 5, which is operated from a motor in the cabinet through change speed gearing indicated at 53. The shaft 52, is shown as extending from front to rear and as carrying a worm 54, in mesh with a worm gear 55, on the lower end of the table cam shaft 23, and as carrying at the rear a spiral gear 66, in mesh with a corresponding gear 57, on a shaft 58, which through bevel gearing 59, is coupled in driving relation to vertical shaft 51.

To enable the proper correlation of the two sets of cams and the proper setting of the cams in respect to the table and the cutter head, provision is made for uncoupling the worm drive shafts 52 and 49, and for independently adjusting the same.

Accordingly, the shaft 52, is "split" or separated at 60, in two sections with the forward, motor driven section carrying a slidingly keyed movable clutch member 61, and the rearward section 52a, carrying worm 54, provided with a companion fixed clutch element 62. When this clutch is open as in Fig. 5, the rearward worm carrying section 52a, of the main shaft may be turned one way or the other by means of a hand crank 63, removably engaged over the end of a short cross shaft 64, carrying a spiral gear 65, in mesh with spiral gear 56, on shaft 52a.

Similarly, the upright shaft is split at 67, with the lower section carrying a sliding keyed clutch member 68, for engagement with a companion clutch element 69, fixed on the upper shaft section and the worm shaft 49, has an exposed end adapted to receive a hand crank 70. Thus when clutch 68, 69, is opened as by means of a hand lever 71, pivoted at 72, and connected with the sliding clutch element at 73, shaft 49, may be turned by crank 70, to set the cams 41, 44, in respect to the cutter head and also in relation to the worktable cams.

The cutter head is further independently vertically adjustable in the illustration, Fig. 1, by constructing said head as a unit adjustable with respect to the rack 35, and providing a screw shaft 74, having a bearing in the head at 75, and screw-threaded engagement with the rack at 76. To facilitate quick adjustment of this screw shaft, particularly when the upper end of the shaft is below the top of the column as in Fig. 1, an outwardly inclined adjusting shaft 77, is shown connected at its lower end with the screw

shaft by angle gearing 78, and having its upper end exposed to receive a hand crank 79.

To provide ready access to the cutter head operating cams at the front and the cam driving gearing at the back, removable doors may be provided at the front and back of the hollow column, over these parts substantially as indicated at 80, 81, Fig. 7.

The clutch 61, 62, on the main drive shaft, in addition to enabling the cam setting for the work table, serves as in the patent first identified, as a throw-out clutch for stopping operations of the machine at the end of a predetermined cycle.

For such purposes, the sliding clutch element is controlled by a fork 82, pivoted at 83, and having an angularly projecting arm 84, to which is connected one end of a clutch throw-out spring 85. The opposite end of this spring is connected with a latch lever 86, pivoted at 87, and carrying a latch nose 88, for holding engagement with a lug 89, projected downward from one side of the clutch fork 82. This one spring thus serves both to yieldingly support the latch lever in cooperating relation with the lug of the clutch yoke and to shift the yoke in the clutch opening direction when the latch lever is tripped from holding engagement with the lug.

The latch lever is automatically operated at the end of the cycle as in the patent application referred to by a projection or pin, such as indicated at 90, on the worm gear 55, engaging the inclined or cam projection 91, adjustably mounted on the end of the latch lever.

Hand control of the clutch 61, 62, is provided in the illustration, by a handle 92, on the outer end of a shaft 93, Figs. 5 and 8, connected by rock arm 94 and link 95, with the arm 96, of the shaft 83, on which the yoke is pivotally supported, said shaft having a downwardly extended arm 97, for pushing the yoke laterally in a clutch closing direction and an angularly related arm 98, engaging an upstanding portion 99, of the latch lever for pushing the latter downwardly in a clutch releasing direction.

It will be clear from Fig. 8, that downward motion of the control handle, rocking shaft 93, in counterclockwise direction will have the effect through the arm 97, of pushing the sliding clutch member 61, into coupled engagement with fixed clutch member 62, and that in such movement, the lug 89, of the clutch yoke will ride up over and engage behind the shoulder 88, of the latch lever, the latter yielding through spring support 85, for such engagement of parts.

To throw out the main clutch either for purposes of setting the table cams or for stopping the machine at any time, the control handle is lifted, Fig. 8, thus to rock the shaft 93, in clockwise direction and this has the effect of depressing the overstanding arm 98, and thus through the stud 99, to force the latch lever downward to make it release the clutch yoke at 88, 89, and permit the spring 85, to snap the movable clutch element out of engagement with the companion clutch element.

If desired, a stop or stops may be provided which can be set to predetermine the limit of movement of either or both the horizontally traveling table or the vertically shiftable cutter head and which will thus fix the movement or movements of these parts independently of possible inaccuracy which might arise from wearing of the cams.

What is claimed is:

1. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions.

2. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions, a power source and drive connections from said power source to said cam shaft including a disconnecting clutch and means for arbitrarily setting said cam shaft in different angular relations when said clutch is disconnected.

3. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions and means for operating said cam shaft including a power shaft, a disconnecting clutch, worm and gear drive to said cam shaft and means for turning said worm and gear drive independently of said power shaft.

4. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions, said carriage being mounted for vertical movement and a horizontal cutter spindle mounted on said carriage.

5. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions, said carriage being mounted for vertical movement and a horizontal cutter spindle mounted on said carriage and means for effecting vertical adjustments of said cutter spindle on said carriage in-

dependently of the vertical shifting movements of said carriage.

6. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions, said carriage being mounted for horizontal travel and a weight connected with said carriage for imparting motion to the same in one direction.

7. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions, a hollow column supporting said carriage for vertical movement at one side of the same, a supporting partition in said hollow column, said shaft being journalled in said partition with said cams at one side of said partition and drive means for said shaft at the opposite side of said partition.

8. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions, a hollow

column supporting said carriage for vertical movement at one side of the same, a supporting partition in said hollow column, said shaft being journalled in said partition with said cams at one side of said partition, drive means for said shaft at the opposite side of said partition and including a worm gear on the shaft, a worm in engagement with said worm gear, power means for turning said worm and manually operable means for turning said worm independently of said power means.

9. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides by said cam followers, said edge cams designed respectively to control desired movement of said carriage in opposite directions, said lever having a gear segment, a rack engaged thereby and means adjustably connecting said rack with said carriage.

10. In a milling machine, the combination of a carriage mounted for travel in opposite directions, a pivotally mounted lever connected for operating said carriage, cam followers on said lever at opposite sides of the pivotal axis of said lever and in different positions longitudinally of

said pivotal axis, a single cam shaft and separate edge cams on said shaft in line with and engaged on opposite sides by said cam followers, said edge cams designed respectively to control desired movement of said carriage in opposite directions, a column supporting said carriage for vertical movement, said cam shaft being journalled on said column in horizontal position, a worm gear on said cam shaft, a horizontally disposed shaft, a worm on said latter shaft in engagement with said worm gear, means for effecting hand adjustment of said worm shaft, a vertically extending shaft in driving connection with said worm shaft and a disconnecting clutch on said vertical shaft.

11. In a milling machine, the combination of a horizontally reciprocating worktable and a vertically reciprocating cutter head and common drive connections to said horizontally reciprocating worktable and vertically reciprocating cutter head, including disconnecting clutches for uncoupling either the horizontally reciprocating worktable or the vertically reciprocating cutter head from said common drive connections and means for effecting separate independent driving adjustments for said worktable and cutter head when said clutches are uncoupled and comprising hand operated mechanism for shifting said worktable horizontally to different positions and hand operated mechanism for shifting said cutter head vertically to different positions.

12. In a milling machine, the combination of a worktable and a cutter head mounted for reciprocation in angularly related planes and common drive means for effecting reciprocation of said worktable and cutter head in said planes, including means for effecting the coupling of said worktable and cutter head in different relations and comprising a main drive shaft for effecting operation of the worktable, a clutch on said main drive shaft for uncoupling the worktable, hand mechanism for shifting the worktable when so uncoupled, drive shafting from said main drive shaft to said reciprocating cutter head, a clutch interposed in said drive shafting for uncoupling said cutter head and hand mechanism for shifting said cutter head when so uncoupled.

13. In a milling machine, the combination of a horizontally reciprocating worktable and a vertically reciprocating cutter head, a vertically extending shaft, cam means on said shaft for effecting reciprocation of the worktable, a horizontally extending power shaft, worm gearing between said power shaft and cam shaft, a horizontally extending cam shaft, cam means on said shaft for effecting vertical reciprocation of the cutter head and drive shafting from said power shaft to said horizontal cam shaft.

14. In a milling machine, the combination of a horizontally reciprocating worktable and a vertically reciprocating cutter head, a vertically extending shaft, cam means on said shaft for effecting reciprocation of the worktable, a horizontally extending power shaft, worm gearing between said power shaft and cam shaft, a horizontally extending cam shaft, cam means on said shaft for effecting vertical reciprocation of the cutter head and drive shafting from said power shaft to said horizontal cam shaft, including a disconnecting clutch and means for effecting adjustments of said horizontal cam shaft independently of said power shaft and vertical cam shaft.

15. In a milling machine, the combination of a horizontally reciprocating worktable and a vertically reciprocating cutter head, a vertically extending shaft, cam means on said shaft for effecting reciprocation of the worktable, a horizontally extending power shaft, worm gearing between said power shaft and cam shaft, a horizontally extending cam shaft, cam means on said shaft for effecting vertical reciprocation of the cutter head and drive shafting from said power shaft to said horizontal cam shaft, a disconnecting clutch on said power shaft, means for automatically operating said disconnecting clutch and means for arbitrarily controlling said clutch.

16. In a milling machine, the combination of a carriage mounted for travel in opposite directions, a cam shaft, two edge cams on said cam shaft, lever arms divergent from a common center and cooperatively related with the respective edge cams at opposite sides of said cams and whereby said lever arms will be oscillated in opposite directions by said edge cams and actuating connections from said lever arms to said carriage for reciprocating the latter in opposite directions.

17. In a milling machine, the combination of a carriage mounted for travel in opposite directions, a cam shaft, two edge cams on said cam shaft, lever arms divergent from a common center and cooperatively related with the respective edge cams at opposite sides of said cams and whereby said lever arms will be oscillated in opposite directions by said edge cams, actuating connections from said lever arms to said carriage for reciprocating the latter in opposite directions and yielding means for imparting travel to said carriage in one direction independently of the travel imparted thereto in the same direction by one of said cams.

18. In a milling machine, the combination of a carriage mounted for travel in opposite directions, a pivotally mounted lever connected for operating said carriage, cam followers on said lever at opposite sides of the pivotal axis of said lever and in different positions longitudinally of said pivotal axis, a single cam shaft and separate edge cams on said shaft in line with and engaged on opposite sides of said cam followers, said edge cams designed respectively to control desired movement of said carriage in opposite directions, a cutter spindle mounted on said carriage and means for effecting adjustments of said cutter spindle on said carriage independently of the shifting movements of said carriage.

19. In a milling machine, the combination of a horizontally reciprocating worktable and a vertically reciprocating cutter head, a main drive shaft having a split portion, a clutch for effecting the coupling and uncoupling of the split portion of said drive shaft, operating connections from the clutch controlled split portion of said drive shaft to said horizontally reciprocating worktable, a hand shaft for effecting operation of the split portion of said drive shaft when said clutch is uncoupled and drive connections from said split portion of the drive shaft to the vertically reciprocating cutter head and including shafting, a clutch interposed in said shafting and hand means for effecting rotation of a portion of said shafting when said last mentioned clutch is uncoupled.

FREDERICK KOCH.
